UNITED STATES PATENT OFFICE.

FRANK F. GIBFORD, OF ENGLEWOOD, ILLINOIS.

ARTIFICIAL-STONE PAVEMENT.

SPECIFICATION forming part of Letters Patent No. 378,000, dated February 14, 1888.

Application filed August 12, 1887. Serial No. 246,798. (No model.)

To all whom it may concern:

Be it known that I, FRANK F. GIBFORD, a citizen of the United States, residing at Englewood, in the county of Cook and State of

5 Illinois, have invented certain new and useful Improvements in Artificial-Stone Pavements; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention has relation to artificial-stone pavements; and the object is to provide a simple, cheap, and durable pavement, of the class described, that will present a true surface for wear, and at the same time obviate all tendency to cracks, separation at the joints, or irregularities in the surface; and to these ends the novelty consists in the construction of the 20 same, as will be hereinafter more fully described, and particularly pointed out in the 25 claim.

In the accompanying drawings, the same letters of reference indicate like parts of the invention.

Figure 1 is a top plan view of a section of 30 my new pavement. Fig. 2 is a reverse or bottom plan view of the same, and Fig. 3 is a bottom perspective view of one of the blocks forming the pavement.

The pavement proper consists of a series of 35 blocks, A, provided with integral projections

a and recesses b, said projections and recesses being flush with the bottom of the block and extending upward about one-half the thickness of the block.

The top surface of the blocks is a true square, 40 and consequently the pavement may be extended indefinitely by simply alternating the sides of the blocks as they are laid—that is, so arranging them that a side with a projection will be contiguous to a side with a recess. 45

It will be observed that the projections are rectangular in form, while the recesses flare inward, so that when the pavement is set in a bed or layer of cement the cement will fill up the interstices, and when it hardens or sets 50 make it practically a solid sheet of pavement.

The blocks may be pressed or molded of any style of concrete, cement, or tiling and then baked, and of course may be ornamented or colored to suit the taste, and can thus be suited 55 in their cheapest and plainest form to street-walks, while the more elaborate are suitable for all styles of tiling for halls, vestibules, mantels, and the like.

What I claim is—

As a new article of manufacture, a block 60 for pavements, having two of its sides provided with projections, and its two opposite sides provided with recesses, as set forth.

In testimony whereof I affix my signature in 65 presence of two witnesses.

FRANK F. GIBFORD.

Witnesses:

FRED. SCHWARTZ,
JOHN BANKER.
